FOLDABLE EASY CHAIR

Antonio Alvarez Moreno, Calle Ondrid 6, Madrid, Spain
Filed Mar. 21, 1963, Ser. No. 267,019
Claims priority, application Spain, Apr. 13, 1962, 92,510
2 Claims. (Cl. 297—441)

The object of the present invention relates to a foldable easy chair, whose novel features are as follows:

- (a) it is constituted by dismantlable tubular elements that fit into each other in a perfect manner.
- (b) when dismantled, it occupies little space and can be enclosed in a small transportable bag, being very appropriate for camping, beach and similar applications.
- (c) it is complemented by a sensitively triangular shaped canvas, having a pocket at each vertex.
- (d) it is light in weight, very strong, easy to mount and dismantle and very commodious.

In the accompanying drawings an embodiment of the present invention is illustrated by way of an example.

FIG. 1 represents a lateral elevation, FIG. 1A a front view, showing the tubular frame as mounted for use, and FIG. 1B a detail indicating the manner in which one element is inserted into the other.

FIG. 2 represents the foldable canvas and FIG. 2A indicates the elements that should be placed in each pocket for storage and transport of the dismantled chair.

FIG. 3 represents the chair complete and ready for use.

It will be observed that this chair is constituted by eight tubular elements of which the uppermost 1 is circular in shape, 2 and 8 are straight, followed by two curved lengths 3 and 7 and two straight pieces 4 and 6 and finally an arched, closing element, which thus completes the frame, said elements being held by inserting their extremes in the corresponding bushings, whereas a reduction of diameter is applied to this effect, thereby achieving a proper mounting of the frame, provided with three particular points or curved verticles into which the determined pockets applied to the triangular vertices, that constitute the complete chair are inserted.

2

Having dismantled the constitutive elements, the canvas is stretched out, as indicated in FIG. 2 and can then be rolled up and stored or transported.

This object can be manufactured in any desired sizes and appropriate materials, being susceptible to numerous modifications of detail, without dissenting from the essence of the invention, which is such as described in the preceding paragraphs and defined in the appended claims.

What is claimed is:

- 10 1. A foldable easy chair, characterized in that it is constituted by a frame susceptible to be coupled together, consisting of eight tubular lengths, of which one is a semi-circular element forming part of the top portion of the back, two are straight to constitute the lateral portions of said back, another two are curved in an acute angle and form two legs and the arms, another two are straight and form the front portion, whereas the last is curved and serves as a closing element, thus constituting an easy chair in combination with a triangular piece of canvas, having curved vertices provided with a pocket at each vertex for the insertion of one of the three constituent parts of the frame.
- 15 2. A foldable easy chair, according to the preceding claim, characterized in that the canvas, with its pockets, is applied to accommodate the elements of said frame when dismantled and, after being rolled up, to constitute a package for storage or transport with portions of said elements held in said pockets.
